[57] CLAIM

The ornamental design for a hanging lamp assembly, as shown and described.

DESCRIPTION

FIG. 1 is a front perspective view of a hanging lamp assembly showing my new design;

FIG. 2 is a top plan view thereof on an enlarged scale;

FIG. 3 is a front elevational view thereof on an enlarged scale, the rear being a mirror image;

FIG. 4 is a side elevational view thereof on an enlarged scale, the opposite side being a mirror image;

FIG. 5 is a bottom plan view thereof;

FIG. 6 is a front perspective view of a second embodiment of my new design;

FIG. 7 is a rear elevational view thereof;

FIG. 8 is a front perspective view of a third embodiment of my new design;

FIG. 9 is a rear elevational view thereof;

FIG. 10 is a top plan view thereof;

FIG. 11 is a front perspective view of a fourth embodiment of my new design;

FIG. 12 is a rear elevational view thereof;

FIG. 13 is a top plan view thereof;

FIG. 14 is a front perspective view of a fifth embodiment of my new design;

FIG. 15 is a side elevational view thereof;

FIG. 16 is a bottom plan view thereof.
